UNITED STATES PATENT OFFICE.

BERNARD F. SCHULTE, OF CHICAGO, ILLINOIS.

ADVERTISING METHOD AND MEANS.

1,371,521.

Specification of Letters Patent. Patented Mar. 15, 1921.

Application filed February 18, 1920. Serial No. 359,723.

To all whom it may concern:

Be it known that I, BERNARD F. SCHULTE, a citizen of the United States of America, and a resident of Chicago, county of Cook, 5 and State of Illinois, have invented certain new and useful Improvements in Advertising Methods and Means, of which the following is a specification.

This invention relates to methods and 10 means of advertising goods or articles to be worn by the person, and particularly to optical goods such as spectacles, eyeglasses and the like. The main objects of the invention are to provide an improved method of 15 displaying goods of the character referred to, and to provide novel means therefor; to provide means for displaying the goods in a most natural and attractive manner and so as to enhance the display by means of artistic 20 and pleasing effects; and to provide a method and means of the character referred to adapted for interchangeability of different types or styles of the goods referred to.

An illustrative embodiment of this invention is shown in the accompanying drawings, in which—

Figure 1 represents a portrait, preferably in the form of an oil painting on canvas, on which real spectacles of a special or modified form are mounted.

Fig. 2 is an enlarged portion of the portrait shown in Fig. 1 showing the spectacles in more specific detail.

Fig. 3 is a horizontal section at the line 35 3—3 on Fig. 2, and shows how the optical goods are attached.

Fig. 4 is a back view of the structure bearing the portrait shown in Fig. 1 on a reduced scale.

40 In the construction and assemblage shown in the drawings, the eye glasses 1 having special short bows 2 are attached to the backing or canvas which bears the portrait 3 by fastening means 4 in a manner and 45 position to simulate the appearance of such spectacles when actually worn by a person. The bridge 5 is modified in form and adapted for the special purpose herein set forth, as will be explained. The bows 2 are cut off 50 rather short, being only about an inch long, and are inserted through the short vertical slits or holes 6 in the canvas or other material 7 on which the portrait is made, the result being in effect a pictorial foreshortening of the bows to correspond with the true 55 perspective presented by a face view.

The canvas is stretched on a frame 8 and is reinforced by strips of heavy paper or the like as shown at 9 and 10 on Fig. 4, said strips being arranged in the shape of a cross 60 and being glued together where they overlap or cross. In order to simplify the mode of attaching the spectacles, and to provide a secure anchorage therefor, a plate of wood 11 or the like is attached as by means of glue 65 to the back side of said strips at the intersecting point or area, which is arranged to be just back of the eyes on the portrait, so that the pins or nails 4 in the rims 12 may be driven into the wood.

70 The rims 12 may well be substantially flat or planar in shape and the lenses 13 are preferably convex somewhat to truly simulate real spectacles, including appearance in shape as well as effect on the light reflected 75 from the glass. The bridge 5 is flattened somewhat so as to avoid the appearance of an abnormally deep space between the same and the canvas. The ends of said bridge, as at 14 where joined to the rims 12, are depressed and the canvas is accordingly indented or recessed somewhat at these points. 80 Real hinge joints 15 are provided for the bows.

In order to enhance the appearance of a 85 reflection of gold on the skin adjacent to the bridge, a little gilt, or the like is applied to the canvas about this point, as will be understood.

By reason of the special modified construction of spectacles as provided for use 90 in connection with the portrait, they present approximately the true perspective required for such portraits on a flat surface, and appear to a great extent to merge with the rest 95 of the painting. Moreover, they lend a touch of reality and semblance of life to the portrait which without this improvement would be impossible of attainment. The portrait 3 and optical attachments 1 are preferably 100 full life-sized.

Different styles of optical goods may be attached to the same portrait, successively, as the pins 4 may easily be withdrawn.

It is intended in practice, as in fact I 105 have already done, to have the portrait well made, and in a series, and to place each portrait, equipped as described, one at a time in the shop window, and to replace same from time to time in a continuous series. 110 The portraits may well be designed to constitute a systematic series artistically illus-

trating all of the more important styles and embodiments of the class of goods to be advertised.

Although but one specific embodiment of this invention has been herein shown and described, it will be understood that numerous details of the construction shown may be altered or omitted without departing from the spirit of this invention as defined by the following claims.

I claim:

1. A portrait rendered on a flat surface having eye glasses of special fragmentary and abnormally flattish character attached 15 to the object whereon said portrait is rendered, in pictorial semblance of a person wearing spectacles.
2. A device of the character described comprising a backing member having a portrait thereon, an attachment representing eye glasses secured to said member in due pictorial relation to said portrait, a board mounted on said backing member behind said attachment, and fasteners engaging 25 said attachment and extending into said board.
3. A device of the character described comprising a backing member having a por-

trait thereon, an attachment representing spectacles secured to said member in due 30 pictorial relation to said portrait, said attachment including short bow members hinged thereto, the outer ends of which extend through and are hidden by said backing member; and pins extending through 35 said attachment and into said backing member, whereby said attachment is secured.

4. The pictorial method of advertising optical goods adapted for wear, which consists in rendering a portrait on a substantially 40 flat surface, and then attaching thereto an abnormal flattish embodiment of the goods, as for example, spectacles, and then exhibiting the same to the public.

5. A spectacle advertising device comprising 45 a flat backing member of rigid character, adapted to hold fastenings such as small nails and having a portrait thereon, in combination with spectacles of distorted and flattish character provided with holes 50 for fastenings such as the said nails or the like to secure the spectacles in due pictorial relation with said portrait.

Signed at Chicago this 16th day of February, 1920.

BERNARD F. SCHULTE.
